J. L. KIMBALL,

DAMPER REGULATOR MECHANISM FOR STEAM PRESSURE APPARATUS,
APPLICATION FILED MAR. 26, 1915.

1,155,822.

Patented Oct. 5, 1915.

UNITED STATES PATENT OFFICE.

JAMES L. KIMBALL, OF SALEM, MASSACHUSETTS, ASSIGNOR TO WALTER G. RUGGLES CO., OF BOSTON, MASSACHUSETTS, A CORPORATION OF MASSACHUSETTS.

DAMPER-REGULATOR MECHANISM FOR STEAM-PRESSURE APPARATUS.

1,155,822.

Specification of Letters Patent.

Patented Oct. 5, 1915.

Application filed March 26, 1915. Serial No. 17,297.

To all whom it may concern:

Be it known that I, JAMES L. KIMBALL, a citizen of the United States, residing at Salem, in the county of Essex and State of Massachusetts, have invented an Improvement in Damper-Regulator Mechanism for Steam-Pressure Apparatus, of which the following is a specification.

This invention relates to the damper regulator mechanism of steam pressure apparatus and has to do more particularly with improved means for controlling the flow of fluid to the motor operating the damper in an apparatus of this character which may 15 be of the type shown in the patent to Locke, No. 398,164, patented November 20, 1888.

As is well known the best results are obtained in a steam generating plant with a damper regulator which will hold the damper at a partial stroke, only allowing sufficient hot gases to enter the flue to create the necessary draft to burn the coal and keep up a uniform pressure. In the damper regulators for this purpose in the prior art so far 25 as known to me the controlling valve mechanism for the motor which operates the damper is formed with a sliding spindle controlling the ports and in order to prevent leakage it is necessary to have a considerable lap over the ports. This results in lost motion between the damper and its controller mechanism producing objectionable variations in steam pressure and a corresponding loss in heat units. It will be understood that in an apparatus of this type, whether the draft be forced, induced or natural it should be automatically regulated within very close limits, and this regulation should be accomplished gradually yet with 30 a precision that will insure steady steam pressure and the best furnace conditions.

In accordance with the present invention the damper and its motor are equipped with a pilot valve connected to be governed by the steam pressure, and of a type wherein the inlet port to the motor and also the exhaust are controlled in proper sequence without any lap or lost motion and in a manner so that a quick and delicate response is had to 45 movements given the valve stem or the valve body as the steam governor and the damper motor operate. To these ends I provide a valve body with a valve device therein consisting in a sleeve formed with a conical tip

constituting one valve member and a stem 55 slidable within such sleeve constituting another valve member, one of said valve members being adapted to control the exhaust from the motor, the other the inlet thereto.

The invention will be better understood 60 from the following detailed description taken in connection with the accompanying drawings and will be thereafter pointed out in the appended claims.

Referring to the drawings: Figure 1 65 shows in central vertical section a valve device constructed in accordance with my invention; and Fig. 2 is a fragmentary elevation at right angles to Fig. 1 showing the yoke device for operating the valve. Fig. 70 3, is a side elevation of the valve-device associated with the motor.

The valve body is indicated at 10 with a nipple connection 11 at one side which may lead through a pipe 12 to the motor 13. In 75 practice this valve body may have a small range of vertical movement imparted thereto by means similar to that of said Locke patent, the pipe 12 springing sufficiently to permit this. An inlet nipple connection 80 is indicated at 14 and an exhaust connection at 15, though it will be understood that in certain aspects of the invention these are interchangeable. These several connections lead to a longitudinal bore 16 which is 85 closed at its lower end by a threaded cap 17 fitted in the bore 16. Between the inlet 14 and the motor connection 11 is a block 18 having a bore therethrough and a conical seat 19 at its top for a conical valve for- 90 mation 20 at the lower end of a sleeve 21 which is slidably fitted in the upper part of the bore 16 being guided through hollow blocks 22 fitted in said bore at each side of the exhaust connection 15. The sleeve 21 95 has in the lower part thereof and opposite the motor connection 11 apertures 23, and spaced thereabove opposite the exhaust connection 15 other apertures 24. The passage to the exhaust from the motor connection 100 through these apertures is controlled by a stem 25 slidably fitted in said sleeve with a reduced portion 26 just below the apertures 24 adapted to permit the passage of fluid and a valve head 27 at its lower end. The 105 valve head 27 is shown as equipped with a conical upper face 28 adapted when raised to the position shown to seat on a

corresponding formation of the sleeve and close the passage through the sleeve, the valve head below this valve seat being of cylindrical plug form fitting closely the reduced walls of the sleeve opposite the apertures 23 as seen at 29 so as to coöperate for completely cutting off the steam. The stem 25 is held normally lifted with relation to the sleeve so that the valve 28 is closed by a coil spring 30 reacting between the end of the sleeve and an adjustable stop collar 31 on the stem. An operating yoke is indicated at 32 for lifting the inlet valve 20 or closing the same and lifting the exhaust valve 28 according to the steam pressure conditions, this yoke being connected for actuation by the governor as set forth in said patent.

It will be understood that whenever a slight reduction in the steam pressure occurs the yoke 32 will be moved downward by the governor beam, thus moving the stem 25 downward and opening the exhaust valve 28. Thereupon the piston of the motor will move downward as the water exhausts, and presently the body 10 of the valve will be moved downward by the cut off cam as explained in said patent, resulting in again closing the exhaust. Thus the damper is opened slightly and remains in this position until a further change of steam pressure takes place. In the event of a further reduction in the steam pressure, these movements will be repeated until the piston of the motor 13 reaches its lowermost position, *i. e.*, the end of its stroke, in which position the damper is wide open. Upon a rise in steam pressure the stem of the exhaust valve is first lifted far enough to close the exhaust, and it arrives at its point when the steam pressure becomes normal. Upon a further rise in steam pressure, above normal, the valve stem 25 will be further lifted by the yoke connection to the steam governor and in this movement as the valve 28 engages its seat it lifts the sleeve 21 therewith, raising the inlet valve 20 from its seat and admitting water to the motor, whereupon the piston of the motor rises until by the cam action described, the valve body is lifted closing the admission valve. Further increase of steam pressure will of course repeat this operation until the damper is fully closed.

It is to be noted that in the described operations the valve structure set forth is adapted to respond instantly to variations in steam pressure, and open either the exhaust or the inlet valve as required with the smallest movement imparted to the valve stem from the yoke 32. Further, that while the valve design is simple and substantial with an entire absence of intricate parts that would be liable to break or get out of order, it is adapted to effect a tight and reliable closure

of the ports in each case and is especially adapted to coöperate with a steam pressure apparatus of the type set forth because it is specially designed to hold the motor at an intermediate position with a capability of sensitive response for varying such position according to the operation of the steam pressure controller.

I do not desire to be limited in all respects to the illustrative details of construction shown and refer to the appended claims rather than to the foregoing description to indicate the scope of the invention.

Having described my invention, what I claim as new and desire to secure by Letters Patent is:

1. Apparatus of the kind described, comprising a valve body having inlet and exhaust ports and an intermediate delivery port, and a valve stem slidably arranged in said body and having slidably mounted thereon a sleeve, said sleeve having at its end a valve adapted to be pressed against a seat for controlling the passage from said delivery port to one of the other ports, said sleeve having a passage therethrough from said delivery port to the third port with a valve seat formation, and said stem having a valve to fit said seat and close said passage, said valves being arranged to open the one by a movement of said stem in one direction, and the other by a movement of the stem in the other direction.

2. Apparatus of the kind described, comprising a valve body having a delivery port with inlet and exhaust ports leading thereto, and a valve stem slidably arranged in said body to control said ports, said stem having a sleeve slidably mounted thereon with a valve formation at its end adapted to be pressed against a seat controlling the passage from said inlet port to said delivery port, said sleeve having a passage therethrough from said delivery port to said exhaust port and said stem having a valve for controlling said passage adapted to be pressed against a seat in said sleeve and to open by a relative movement between the stem and sleeve in a direction opposite to the opening movement of the valve at the end of said sleeve.

3. Apparatus of the kind described, comprising a valve body having a delivery port with inlet and exhaust ports leading thereto, and a valve stem slidably arranged in said body to control said ports, said stem having a sleeve slidably mounted thereon with a valve formation at its end adapted to be pressed against a seat controlling the passage from said inlet port to said delivery port, said sleeve having a passage therethrough from said delivery port to said exhaust port and said stem having a valve for controlling said passage adapted to be pressed against a seat in said sleeve and to

open by a relative movement between the stem and sleeve in a direction opposite to the opening movement of the valve at the end of said sleeve, and a spring coacting between said sleeve and said stem for normally holding the valve on said stem against its seat in said sleeve.

In testimony whereof, I have signed my name to this specification, in the presence of two subscribing witnesses.

JAMES L. KIMBALL.
